UNITED STATES PATENT OFFICE.

CHARLES ALBERT BALL, OF MARION, INDIANA.

DESIGN FOR A BADGE.

SPECIFICATION forming part of Design No. 21,643, dated June 21, 1892.

Application filed April 22, 1892. Serial No. 430,268. Term of patent 3½ years.

To all whom it may concern:

Be it known that I, CHARLES ALBERT BALL, a citizen of the United States, residing at Marion, in the county of Grant and State of Indiana, have invented and produced a new and original Design for Medals and Badges, of which the following is a specification, reference being had to the accompanying drawings, forming a part thereof, in which—

10 Figures 1 and 2 represent, respectively, the obverse and the reverse of a medal or badge embodying my new design.

The design is distinguished by its general effect, and the drawings are mainly relied upon to elucidate its general features, the following general description being given for the purpose of this specification.

Upon both the obverse and the reverse sides of the badge or medal a dove is represented as resting upon a floral spray of the character of the golden-rod, and the dove and the golden-rod appear as surmounting a ribbon-like panel, the panel being decorated

with a figure simulating the coat of arms of the United States. A disk or medallion figure appears as suspended from the ribbon-like panel, and the obverse side of the medallion figure is decorated with a pictorial representation of the landing of Columbus. The reverse side of the disk or medallion figure is ornamented with the representation of a building simulating the Woman's Building of the Columbian Exposition. 25 30

I claim—

1. The design for the medal or badge, substantially as herein shown and described. 35

2. In the design for the medal or badge, the obverse side, substantially as herein shown and described.

3. In the design for the medal or badge, the reverse side, substantially as herein shown and described. 40

CHARLES ALBERT BALL.
